PUMP

David B. Baker, Riverside, Ill., assignor to
International Harvester Company, a corpora-
tion of New Jersey

Application May 27, 1937, Serial No. 144,990

19 Claims. (Cl. 230—79)

This invention relates to improvements in gas moving devices. More particularly it relates to means for mounting an impeller or rotor in a device particularly adapted for air compressors or 5 vacuum pumps.

An example of such a device is found in the Nash Patent 1,091,529, March 31, 1914, which shows an impeller type of pump in which the spaces between the rotor or impeller blades form 10 buckets. The impeller is usually driven by an electric motor, being preferably mounted on the motor shaft for rotation therewith. By rotation of the impeller the liquid is thrown outwardly therefrom into an enlarged portion of the impeller casing, thereby producing a suction. Due 15 to the shape of the casing the liquid moves around a smooth wall thereof and is again picked up by the impeller blades, thereby filling the buckets formed by the blades and discharging 20 the gas therein. This type of pump has been found to have a particular utility in combination with apparatus requiring delivery of air for a predetermined length of time, as disclosed and claimed in assignee's Patents Nos. 2,077,871, April 25, 1937, and 2,124,185, July 19, 1938, relating to Milk refrigerating cabinets.

As disclosed in said patents, however, the rotor or impeller is rigidly secured to the motor shaft and no provision is made in the drive connection 30 between the shaft and the impeller to allow relative axial movement, however slight. It is found that this slight relative movement is desirable, in as much as the bearings in few motors permit perfect alignment and axial positioning of the 35 motor shaft with respect to mechanism driven thereby, unless said motors are provided with high grade ball bearings. In manufacturing experience with pumps of the type hereinbefore referred to, it was found difficult to manufacture 40 the pump in the form in which the rotor or impeller was rigidly secured to the motor shaft.

For instance, the impeller, which is rigidly secured to the motor shaft, must operate within the impeller chamber and very close to the axially 45 opposite walls thereof without touching. In specific instances, this clearance should be generally about .003 inch to .005 inch. If the impeller and the rear wall of the impeller chamber touch, when made of metal, a roughening of the 50 two surfaces results, which increases the running clearance therebetween. If the running clearance between the impeller and the wall is excessive, then a considerable amount of air leakage occurs, detracting from the efficiency of the 55 pump. In addition, the motor shaft on which

the impeller is secured must be held carefully by special bearings so that no appreciable amount of end motion can take place.

It is, therefore, desirable to simplify manufacturing of the pump, in as much as simplification 5 provides an improved pump and reduces manufacturing costs thereof. In the present improved construction of the pump, the impeller is mounted on the motor shaft in a manner permitting relative axial movement and means are carried by 10 the shaft for driving the impeller. At the same time, it is found desirable to employ an impeller made of a non-metallic material, such as hardened fibrous material, a phenolic condensation product, or the like, that is very resistant to 15 water absorption. By making the impeller of this material, the complications resulting from rubbing between the impeller and the chamber wall are eliminated and the impeller is free to move axially with respect to the motor shaft 20 within the impeller chamber.

The principal object of the invention, therefore, is the mounting of the impeller on the motor shaft in a manner permitting relative axial movement therebetween.

An important object of the invention is to provide 25 an impeller composed of non-metallic material, as hereinbefore mentioned.

Another important object of the invention is to provide the impeller with a metal bushing in 30 its hub to provide a bearing surface.

Another object of the invention is to provide means on the motor shaft for driving the impeller.

Still another object is to make the above 35 provision in such a manner as will permit easy removal and installation of the impeller and the component parts of the means forming the drive connection.

Still another object is generally to provide 40 means for allowing the impeller to float on the motor shaft within the limits of the impeller chamber.

Specifically, an important object of the invention is to provide a member rigidly secured to the 45 motor shaft for rotation therewith and on which is carried, for axial movement with respect thereto, the impeller, said impeller being driven by a drive member associated with the sleeve and the shaft for rotation therewith.

Briefly and specifically, these and other important objects are attained in a pump of the type hereinbefore referred to by the provision 50 of a drive sleeve secured to the motor shaft, a rotor or impeller carried thereon for axial move- 55

ment with respect thereto and a driving connection between the shaft and the impeller for rotating the impeller with the shaft.

A further understanding of the objects and desirable features of the invention may be had from the following description taken in connection with the illustrations of a preferred construction as shown in the accompanying sheets of drawings, in which:

10 Figure 1 is an end elevation of the assembled pump;

Figure 2 is a substantially vertical section taken on the line 2—2 of Figure 1;

15 Figure 3 is an elevation of the outer conduit plate;

Figure 4 is an elevation of the front side of the conduit plate;

20 Figure 5 is an elevation of the open side of the main casing with the impeller shown in position and with a liquid sealing medium indicated by broken line;

25 Figure 6 is an elevation of the closed side of the impeller showing the driving connection with the shaft;

30 Figures 7 and 8 are respective side and end elevations of the impeller drive sleeve showing the means thereon for engaging the impeller driving member; and,

Figure 9 is a detailed end view of the drive member.

The pump illustrated herein consists essentially of four principal elements. The main casing 10 is secured by brackets 11 to an electric motor 12, a portion of which is shown in Figures 35 1 and 2. The main casing 10 is provided with an impeller chamber 13, being closed at one side by the conduit plate 14 and a gasket 14' and closed at the axially opposite side by a rear wall 10a formed as an integral part of the casing 10. 40 The conduit plate 14 and a cover plate 14a are held in place on the main casing 10 by a plurality of cap screws. An impeller or rotor 15 is driven by the motor shaft 16 and is rotatably mounted in the main casing in the impeller 45 chamber 13. With these main elements being generally described, their relation will be described in detail.

The impeller 15 is preferably composed of a non-metallic material, as hereinbefore referred 50 to, and is provided with a hub 17 into the central bore of which is fitted, for rotation therewith, a metal bushing 18. When the impeller is molded as a phenolic condensation product, the metal bushing 18 is preferably molded directly 55 therein. This metal bushing 18 provides a bearing for the impeller on a drive sleeve 19 which is keyed by a key 19a onto an extension of the motor shaft 16. The drive sleeve 19 is cut out at one end to provide a pair of diametrically opposed lugs 20 which form means for engaging 60 corresponding openings formed in an impeller drive member or means 21 carried by the shaft 16. The openings in the member 21 for mounting the same on the shaft 16 and for engagement 65 with the drive sleeve 19 are best shown in Figures 6 and 9. In this manner, it may be said that the motor shaft 16 carries the drive member 21 for rotation therewith. The drive member 21 abuts a shoulder formed on the shaft 16 70 and is held against axial displacement by a cap screw 22 threaded into the free end of the shaft.

The above described construction is preferred as a matter of simplicity in manufacturing and also to allow for the utilization in former constructions of the improved impeller construc-

tion embodied in the present invention without materially altering the parts of the former construction. It will be understood, then, that the drive sleeve 19 and the impeller drive member 21 may or may not be formed integral, and 5 either may be keyed to the motor shaft 16. In the present instance, the drive member 21 is formed with one or more radially extending portions including a driving lug 21a which engages one of a plurality of angularly spaced web portions formed by axially extending, arcuate recesses disposed about the hub 17 of the impeller 15, as best shown in Figure 6. The webs and recesses are formed generally for the purpose of decreasing the weight of the impeller and at 10 the same time to reinforce and strengthen the central portion thereof. With these provisions made, a simple and efficient driving connection 15 may be effected between the impeller and the drive member 21, wherein the driving lug 21a 20 axially enters an aforesaid recess and abuts a web in driving relation.

Generally, the arcuate distance between the webs, as shown in Figure 6 is considerably extensive, and while more relative angular movement is permitted than is needed between the impeller and the drive element, it does not detract from the operation of the pump; and at the same time the result serves as a feature of the invention. In short, since the aforesaid recesses and webs are provided in the impeller for other reasons, it is not undesirable to take advantage of the same to establish part of the means for driving the impeller. In any event, in order to simplify manufacture of the pump, some 35 means of engagement between the drive member and the impeller would have to be provided, and in order to prevent binding between these two parts, such means would almost of necessity have to permit relative angular movement between the 40 two, unless expensive finishing processes be resorted to.

Adjacent the rear wall 10a of the pump casing 10, the motor shaft 16 is provided with appropriate means 23 for throwing liquid outwardly during 45 rotation of the impeller, thereby preventing liquid from reaching the bearings of the motor. This means 23 is positioned between the drive member 21 and a second shoulder or flange formed on the shaft 16. 50

From the outer end of the hub 17 of the impeller 15, a radial flange 24 extends outwardly to connect the hub with a cylindrical flange 25 which forms the base for spirally arranged, circumferentially spaced impeller blades 26. At 55 the outer ends, the spaces between the impeller blades, which may be termed as pockets, are open on the radial face of the impeller. At the other end, the spaces are sealed by a radial flange 27. At its periphery, said flange is provided with 60 an annular lip 28, which is utilized, as will be hereinafter described, to reduce the amount of liquid which by-passes the impeller on the inner face.

The main casing 10 is provided, as previously stated, with an impeller chamber 13. Said chamber is substantially cylindrical at each end with the two ends spaced apart and joined by flattened side walls. A construction is thereby formed which might be 70 termed as somewhat elliptical in shape and having a smooth inner contour, around which fluid may readily flow with a minimum of resistance. As best shown in Figure 5, the impeller chamber 75 is arranged with its larger dimension at an angle

with respect to vertical of substantially 45 degrees.

Adjacent the motor, the casing 10 is formed with an opening 29, through which the motor shaft extends. It will be noted that there is no contact between the motor shaft and the parts carried thereby with the casing or parts mounted thereon. At the end through which the motor shaft extends, the casing 10 is provided with a cylindrical recess 30 in which a sealing sleeve 31 is tightly fitted. Said sleeve carries a radial flange which terminates closely adjacent the sealing means 23. Any liquid which escapes around the impeller must pass between the edge of said flange and said means. The liquid then is thrown outwardly by the means into the cylindrical recess 30. A drain conduit 32 communicates with the cylindrical recess through an opening formed in the sleeve 31. Said drain conduit extends downwardly and across the bottom of the casing communicating with the air inlet means to the casing, as will be hereinafter described.

It will be noted that the inner wall 10a of the casing 10 is provided with a shoulder 33 within the impeller chamber 13. This shoulder 33 lies closely adjacent the impeller 15 and over-hangs the periphery of the flange 27 thereon. Adjacent the shoulder 33 and at right angles thereto, the inner wall 10a is provided with an annular machined or finished surface 10b. The impeller 15, at its inner end, is also provided with an annular finished surface 15a which cooperates with the annular surface 10b to prevent leakage of liquid or air from the impeller chamber 13. Because of the composition of the impeller 15 of non-metallic material, as hereinbefore described, the liquid provides ample lubrication to compensate for contact of the surfaces 15a and 10b while the impeller 15 is floating axially on the shaft 16 within the impeller chamber 13. This construction is made possible only by provision of the drive connection embodied in the present invention, and a minimum amount of liquid escapes past the impeller without an actual constantly contacting seal. The small amount of liquid which does escape is drawn back into the system through the drain 32. An important advantage of this construction lies in the fact that the impeller is free to float axially without damage to surfaces 10b and 15a, and therefore, no special provision for lubrication is required.

There is also an advantage in the fact that when the impeller is running idle, that is without the supply of liquid, there is no bearing friction present and no resulting load therefrom on the motor because of the aforesaid relative axial movement.

The conduit plate 14, as shown in Figures 3 and 4, is provided with an inlet conduit 34, which terminates at its lower end in a tubular extension 35 on which a flexible hose may be fitted. Said inlet conduit communicates with two branch inlet conduits 36 extending through the plate. The outlet ends of said conduits are diametrically opposite each other. The conduits terminate at the open ends of the pockets formed by the impeller blades adjacent the bottom walls thereof, which are formed by the flange 25. As the liquid is thrown from the pockets air is drawn in through the inlet conduits 36.

It will be noted in Figure 2 that at its point of communication with the conduit plate 14, the extension 35 is flattened and restricted in cross section. A nozzle effect is thereby obtained with

an expanding stream of air. Liquid from the drain conduit 32, which communicates with the inlet conduit at this point, is entrained and carried with the inlet air back into the impeller chamber.

A small drain opening 32' is formed in the conduit plate 14. Said opening forms a communication between the impeller chamber 17 and the inlet conduit 34 and provides a drain for the chamber when the pump is not in operation.

For supplying liquid to the pump to initiate operation, a filling conduit 37 connecting with the lower branch inlet conduit 35 extends upwardly through the conduit plate and communicates with a filling conduit 38 formed in the casing 10. Said conduit communicates with an enlarged filler neck 39 covered by a cap 40. Said cap closely fits over the top of the filling neck and is pivoted for swinging upwardly when water is supplied.

It will be understood that suction produced by the impeller in the inlet conduits will act to maintain the cover 40 in a closed position. Such air as may be drawn in around the filler cap does not impair operation of the pump. By means of a filler arrangement of this type, liquid may be added while the motor and impeller are in operation.

As the impeller rotates, liquid, which had been previously thrown out to the enlarged ends of the impeller casing, moves around the wall thereof and is engaged by the impeller blades thereby filling the pockets thereof. The displacement of air brought about by this action results in the movement of air through the outlet openings 41.

The outlet openings 41 communicate with outlet conduits 42 leading upwardly and merging into an outlet conduit 43, which discharges at a high point in the casing into a liquid chamber 44 formed in the upper portion of the casing above the impeller chamber 13. Because of the high speed of an electric motor, considerable agitation is produced in the impeller chamber with the result that a considerable percentage of the liquid therein escapes with the air discharged therefrom. Mixture of air and water is discharged into the liquid chamber with a substantial percentage of the water separating therefrom. A certain amount of the water entrained as a fine mist by the air is discharged from the upper end of the water chamber through an opening communicating with a discharge conduit 45 formed in the conduit plate 14. Said conduit, as best shown in Figure 3, extends to the lower end of the cover plate communicating with an outlet extension 46.

It will be understood that when the device, as described, is put into operation, liquid poured into the filler neck 39 passes into the impeller chamber, filling said chamber completely except for the amount displaced by the impeller blades at each end of the chamber. The liquid supplied in excess of this amount is forced by the impeller through the outlet conduits into the water chamber 44.

It so happens that in the pump disclosed herein, the balance of pressures is such that the impeller is forced toward the wall 10a of the casing 10 with a pressure of approximately one to two pounds total, to be specific, when water is poured into the unit. In this manner, the impeller moves toward the wall 10a and provides perfect sealing between the surfaces 15a of the impeller and 10b of the wall 10a.

The impeller 15 is so constructed and positioned that all of the liquid therein drains to the low point at one side, which is in communication by means of a conduit 47 formed in the conduit 5 plate with the inlet conduit 34. To regulate the flow of water through said conduit, a bore 48 extending through the cover plate and into the conduit plate passes through a restricted portion of the conduit 47. A metering pin 49 is fitted in said bore, being secured therein by a cap-screw 50 on the cover plate 14a. Said metering pin is provided with a transverse metering opening 51 which determines the rate of liquid flow passing through the conduit 47 into the inlet 34.

15 In the operation of the device, water from the chamber 44 is continuously returned to the impeller chamber, thereby replenishing a substantial portion of the amount carried through the outlet conduits. However, as an appreciable amount is carried over through the discharge conduits, the water in the chamber 44 is gradually depleted during operation. When the entire supply has been depleted, the amount in the impeller chamber is soon reduced until it is no longer sufficient to maintain a seal over the impeller blades and to provide for displacing air in the pockets formed by said blades. The suction is then broken at the inlet side of the device with the result that the remaining liquid drains downwardly through the inlet extension 35. By such a construction, the operation of which has been described in connection with the description, a pump is provided which forces air for a predetermined length of time. After the seal has been broken, air is no longer forced through the discharge conduit. A particular advantage of this pump for an operation of this type is that, when effective operation of the pump ceases, there is no friction or wear. The motor, which may be operating other parts, such as the compressor of a cooling system, may continue to run without any appreciable load caused by the impeller, which is merely fanning the air around the impeller chamber, and with no resistance due to friction of pump bearings. Also, while the motor is operating other parts, the motor shaft may have slight axial movement with respect to the impeller, because of the improved drive connection disclosed herein.

50 Thus it will be apparent from the above description, that the assembly of the unit is greatly simplified, and in manufacturing it is necessary only to see that certain clearances exist between the opposite sides of the impeller and the impeller chamber.

It will be understood that applicant has shown only a preferred embodiment of his improvements in the particular type of air moving device disclosed, and that he claims as his invention all modifications falling within the scope of the appended claims.

What is claimed is:

1. In an air pump including a casing formed with an impeller chamber and a shaft extending thereinto, the combination with the shaft of an impeller carried thereby for relative axial movement, and a driving connection between the shaft and the impeller permitting slight relative angular movement therebetween.
2. In an air pump including a casing formed with an impeller chamber and a shaft extending thereinto, the combination with the shaft of a sleeve carried thereby for rotation therewith, an impeller carried on said sleeve for free rela-

tive axial movement, and a driving connection between the sleeve and the impeller.

3. In an air pump including a casing formed with an impeller chamber and a shaft extending thereinto, the combination with the shaft of a sleeve carried thereby for rotation therewith, an impeller carried on said sleeve for free relative axial movement, and means carried by the sleeve for rotation therewith and engaging the impeller for rotating the impeller with the shaft. 10

4. In an air pump including a casing formed with an impeller chamber and a shaft extending thereinto, the combination with the shaft of a sleeve carried thereby for rotation therewith, an impeller carried on said sleeve for free relative axial movement, and means carried by the shaft and engaging the sleeve and the impeller for rotating the impeller with the shaft. 15

5. In an air pump including a casing formed with an impeller chamber and a shaft extending thereinto, the combination with the shaft of a sleeve carried thereby for rotation therewith, an impeller carried on said sleeve for free relative axial movement, a drive member associated with the shaft and the sleeve for rotation therewith 25 and engaging the impeller.

6. In an air pump including a casing formed with an impeller chamber and a shaft extending thereinto, the combination with the shaft of a sleeve carried thereby for rotation therewith, an impeller carried on said sleeve for free relative axial movement, a drive member carried by the shaft and engaging the impeller, and means on the sleeve engaging the drive member for rotation therewith. 35

7. In an air pump including a casing formed with an impeller chamber and a shaft extending thereinto, the combination with the shaft of a sleeve carried by the shaft for rotation therewith, an impeller carried by the sleeve for free relative 40 axial movement, and means associated with the shaft and the impeller and engaged by the sleeve for rotation therewith.

8. In an air pump including a casing formed with an impeller chamber and a shaft extending thereinto, the combination with the shaft of an impeller carried thereby for relative axial movement for cooperating with a wall of the chamber to form an air seal therewith, said impeller being composed of non-metallic material and having a central metal bushing fitted therein to provide a bearing between the impeller and the shaft, and a driving connection between the impeller and the shaft permitting slight relative angular movement therebetween. 50

9. In an air pump including a casing formed with an impeller chamber and a shaft extending thereinto, the combination with the shaft of an impeller carried thereby, said impeller being composed of a non-metallic material and freely movable axially on the shaft to form an air seal with a wall of the impeller chamber, and a drive connection between the shaft and the impeller. 60

10. In an air pump including a casing formed with an impeller chamber and a shaft extending thereinto, the combination with the shaft of a sleeve carried by the shaft for rotation therewith, an impeller carried on the sleeve for axial movement therebetween to form an air seal 70 with a wall of the chamber, a drive member carried on the shaft and engaging the impeller, and a driving lug on the sleeve engaging said drive member to rotate the impeller with the shaft.

11. In an air pump including a casing formed 75

- with an impeller chamber and a shaft extending thereinto, the combination with the shaft of a sleeve carried by the shaft for rotation therewith, an impeller carried on the sleeve for axial movement therebetween to form an air seal with a wall of the chamber, and a radial arm carried by the sleeve for rotation therewith, said arm engaging the impeller for rotation thereof with the shaft. 5
- 10 12. In an air pump including a casing formed with an impeller chamber and a shaft extending thereinto, the combination with the shaft of an impeller carried on the sleeve for relative axial movement therebetween, and a radial arm carried by the shaft for rotation therewith and engaging the impeller for rotation thereof with the shaft. 15
13. In an air pump including a casing formed with an impeller chamber and a shaft extending thereinto, the combination with the shaft of a sleeve carried thereby for rotation therewith, an impeller carried on the sleeve for axial movement with respect thereto, said sleeve being composed of non-metallic material and including a metallic bushing fitted at the center thereof to provide means for mounting the impeller on the sleeve, and a driving member carried by the shaft and engaging the sleeve for rotation therewith, said driving member including a portion engaging the impeller. 20
14. In an air pump including a casing formed with an impeller chamber and a shaft extending thereinto, the combination with the shaft of an impeller disposed concentric with the shaft, a sleeve carried by the shaft for rotation therewith and permitting free relative axial movement between the impeller and the shaft, and a drive member carried by the sleeve for rotation therewith and engaging the impeller. 25
- 30 15. In an air pump including a casing formed with an impeller chamber and a shaft extending thereinto, the combination with the shaft of an impeller disposed concentric with the shaft, a sleeve carried by the shaft for rotation therewith and permitting relative axial movement between the impeller and the shaft, and a drive member carried by the shaft for rotation therewith and engaging the impeller for rotation thereof with the shaft. 35
16. In an air pump including a casing formed with an impeller chamber and a shaft extending thereinto, the combination with the shaft of an impeller disposed concentric with the shaft, a sleeve carried by the shaft for rotation therewith and permitting relative axial movement between the impeller and the shaft, and a drive member carried by the shaft for rotation therewith and engaging the impeller and permitting slight relative angular movement between the impeller and the shaft. 40
17. In an air pump including a casing formed with an impeller chamber and a shaft extending thereinto, the combination with the shaft of a sleeve carried thereby, an impeller carried on the sleeve in a manner permitting free relative movement between the impeller and the shaft, and a driving connection between the shaft and the impeller. 45
18. In an air pump including a casing formed with an impeller chamber and a shaft extending thereinto, the combination with the shaft of a sleeve carried thereby for rotation therewith, an impeller carried on the sleeve for rotation therewith and for free movement axially with respect thereto. 50
19. In an air pump including a casing formed with an impeller chamber and a shaft extending thereinto, the combination with the shaft of an impeller disposed concentric with the shaft for free relative axial movement with respect thereto, a sleeve carried by the shaft for rotation therewith, and a drive member carried by the sleeve and engaging the impeller. 55

DAVID B. BAKER.
